MINER'S PIT-CAP.

No. 838,054.

Specification of Letters Patent.

Patented Dec. 11, 1906.

Application filed June 16, 1905. Serial No. 265,589.

To all whom it may concern:

Be it known that I, ROYAL E. PITCHER, of Osage City, county of Osage, State of Kansas, have invented certain new and useful 5 Improvements in Miners' Pit-Caps, of which the following is a specification.

My invention relates to a class of devices known as "miners' pit-caps," which are caps provided with convenient means for carrying 10 certain small implements used by miners and which should be readily available for use whenever needed.

The object of my invention is to provide in such a cap means for carrying one or more 15 boxes, preferably a match-box and a wick-box, so constructed, respectively, that they tend to keep their place when inserted into their proper positions in the case provided for them in the cap and when in such positions to 20 remain closed, but which are readily accessible to manipulation at need and which when withdrawn from their case open automatically. The automatic action referred to is not only a time-saving convenience, but it affords means for gaining access to the contents 25 of either or any of the receptacles at will through the employment of but one hand either for withdrawing or replacing the receptacle from or into the case.

30 My device comprehends means for carrying a wick-puller with equal convenience and with equal facility of manipulation.

In the accompanying drawings, which constitute a part of this specification, Figure I is 35 a perspective view of a preferred form of embodiment of my invention, showing a cap equipped with a wick-puller and two receptacles, one a match-box and the other a wick-box, the view being taken looking toward the 40 match-box. Fig. II is a vertical section of the receptacle-case detached from the cap and showing both boxes in elevation. The match-box is shown in full lines as confined within the case and in dotted lines in the act 45 of being withdrawn therefrom, its lid being open in consequence of its release from the case. Fig. III is a section as on the line III III of Fig. II, both sides of the case being shown.

50 Referring to the numerals on the drawings, 1 indicates a cap made of any suitable materials and of any preferred contour and preferably provided with a vizor 2. To the fore

part of the cap is secured a case of suitable and preferred shape and dimensions and 55 preferably provided with a crown-plate 3 and a vizor-plate 4, which are secured, as by rivets 5 and 6, to the crown 7 and vizor 2 of the cap, respectively. The case is preferably provided with a front plate 8, which preferably projects sufficiently above the crown 7, as indicated by the reference-numeral 9, to constitute a suitable support for a miner's lamp. (Not illustrated.) The projection above the crown also affords material for the 65 formation of a lug 10, hereinafter referred to. The member above described is denominated a "case" in respect to its function of retaining within it a receptacle for whose accommodation it is provided. As previously set 70 forth, I prefer to locate within it two receptacles—a match-box 14 and a wick-box 15. The match-box preferably opens at the top and the wick-box preferably at the side, but both operate substantially upon the same 75 principle, as hereinafter set forth, and therefore constitute examples of two forms of embodiment thereof.

Each box fits loosely within the case, preferably between its front plate 8 and its back 80 plate 16, so that it may be easily slipped into or out of the case, access to it in each instance being provided for through opposite finger and thumb notches 17 and 18 in the front and back plates, respectively. Where two boxes 85 are employed, they are set, as shown in Fig. II, back to back and are limited in respect to inthrust into the case, as by stop-pins 19. (See Fig. III.)

The characteristic feature of the boxes is 90 that they are provided with springs, which tend to automatically open them and which by reason of that tendency serve to yieldingly hold them in place against accidental dislodgment. The match-box 14 preferably 95 opens at the top, and being provided with a hinged lid 20 at its end is provided with an internal spring 21, disposed and adapted to yieldingly hold the lid open.

The wick-box 15 is provided with a hinged 100 side lid 22, (see Fig. III,) which is provided with a bifurcated spring 23, secured to the end of the box, as indicated at 24, and tending to yieldingly force the lid open. It will therefore be seen that each lid by reason of 105 the resilient action of its spring tends not

only to remain open, but through that tendency, which is overcome by thrusting the box into the case, to remain snugly confined within the case when inserted into it.

5 The wick-box may be made all around of only slightly smaller dimensions than the case which contains it; but I prefer to make the match-box somewhat shorter than the case and in order to bring its lid 20 into operative relation to the top of the case, and to mount it upon a yielding support 25, preferably consisting of a leaf-spring, secured at one end, as indicated at 26, to the bottom of the case and projecting upwardly to make sure of its resiliency making yielding contact with a transverse stop-pin 27. Its free end 28 being suitably curved to conveniently and properly accommodate it to the support of the bottom of the match-box projects a little above the top of its stop-pin 27, so as to engage the bottom of the match-box and to coöperate with the spring 21 to hold the match-box in position within the case and at the same time to counteract the force of the spring 21 to keep the lid 20 closed while the match-box is inserted within the case.

Reverting to the lug 10, above alluded to, which constitutes a preferred horizontal projection for holding the wick-puller 30 in place, it is specified that the said lug is perforated for the accommodation of the straight end 31 of the wick-puller. Opposite to the said perforation, in vertical alignment therewith, I provide a pocket 32 for the accommodation of the hooked end of the wick-puller. The wick-puller may be held in position between the two confining members specified—to wit, 10 and 32—as by a coiled spring 33, surrounding the wick-puller toward its end 31 and held in place thereon, as by a fixed collar 34.

The operation of my device may be understood from the foregoing specification, to which, however, may be added the statement that the wearer of the cap may by thumb and finger manipulation of either of the boxes or of the wick-puller apply force sufficient to dislodge the desired member exerted against the force of its spring retaining member and having withdrawn it find it ready for instant use. When it is to be returned to place, all that is necessary is to gently slip it back into the case or holder provided for it against the opposition of its spring, which, as soon as it is introduced into its proper position, holds it there.

What I claim is—

1. In a miner's pit-cap, the combination with a case thereon and a receptacle fitting

within the case, of means within the receptacle for yieldingly holding it within the case. 60

2. In a miner's cap, the combination with a cap and case thereon, of a receptacle provided with a hinged lid removably fitting within the case and yielding means for holding the receptacle within the case and which at the same time tend to open the lid. 65

3. In a miner's cap, the combination with a case, of a receptacle provided with a hinged lid, means within the receptacle for yieldingly holding the lid open and yielding means within the case coöperative with the said means within the receptacle for holding the receptacle within the case. 70

4. In a miner's cap, the combination with a case open on opposite sides, of a plurality of receptacles within the case and yielding means within said receptacles for holding the receptacles in place within the case. 75

5. In a miner's cap, the combination with a case provided with an apertured lug and pocket alined therewith, of a wick-puller adapted to enter the aperture in the lug and the pocket respectively, and a spring upon the wick-puller for holding the wick-puller in place within said members. 80

6. In a miner's cap, the combination with a case provided with an apertured lug and pocket alined therewith, of a wick-puller adapted to enter the aperture in the lug and the pocket respectively, and yielding means upon the wick-puller for holding the wick-puller in place within said members. 85

7. The combination with a miner's cap provided with a vizor, of a case provided with a crown-plate, front plate and vizor-plate and means for securing the crown-plate and vizor-plate to the crown and the vizor respectively, said front plate being extended above the crown substantially as and for the purpose specified, of an apertured lug bent at right angles from the top of the front plate, and a pocket opposite said lug, said lug and pocket being adapted to hold the wick-puller substantially as set forth. 90

8. In a miner's cap, the combination with a case, of a receptacle provided with a hinged lid, and means within said receptacle adapted to automatically open the lid when the receptacle is removed from said case. 95

In testimony whereof I have hereunto signed my name in the presence of two subscribing witnesses.

ROYAL E. PITCHER.
